US00D990536S

(12) **United States Design Patent** (10) **Patent No.:** **US D990,536 S**
(45) **Date of Patent:** **** Jun. 27, 2023**

(54) **SUPPORT STRUCTURE FOR MARINE WIND
GENERATOR**

(71) Applicant: **Industry-Academic Cooperation Foundation, Kunsan National University, Gunsan-si (KR)**

(72) Inventors: **Dong Hyawn Kim, Sejong-si (KR); Jang Ho Lee, Gunsan-si (KR); Dae Jin Kwag, Gunsan-si (KR)**

(73) Assignee: **INDUSTRY-ACADEMIC COOPERATION FOUNDATION, KUNSAN NATIONAL UNIVERSITY, Gunsan-si (KR)**

(**) Term: **15 Years**

(21) Appl. No.: **29/773,185**

(22) Filed: **Mar. 8, 2021**

(30) **Foreign Application Priority Data**

Sep. 7, 2020 (KR) 30-2020-0042444

(57) **CLAIM**

The ornamental design for a support structure for marine wind generator, as shown and described.

DESCRIPTION

FIG. 1 is a perspective view of support structure for marine wind generator, showing the present design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

1 Claim, 7 Drawing Sheets
